(57) **CLAIM**

The ornamental design for a poop scooper, as shown and described.

DESCRIPTION

FIG. 1 is a first perspective view of a poop scooper showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of an alternate state of the poop scooper thereof;

FIG. 10. is a perspective view of another alternate state of the poop scooper thereof; and,

FIG. 11 is an enlarged view of the selected portion 11 in FIG. 1.

The dashed broken lines illustrate portions of the article that form no part of the claimed design, and the long-short-dash broken lines define the bounds of enlarged views and form no part of the claimed design.

1 Claim, 11 Drawing Sheets
